UNITED STATES PATENT OFFICE.

WILLIAM C. HIERING, OF NEWARK, NEW JERSEY, ASSIGNOR TO J. E. MERGOTT CO.,
OF NEWARK, NEW JERSEY, A CORPORATION OF DELAWARE.

COMBINED BAG CLASP AND CATCH.

Application filed January 22, 1926. Serial No. 82,941.

This invention relates to combined clasps and catches for securing the hinged side elements of a bag frame in closed relation.

One of the objects of the invention is to 5 provide a simple, compact clasp for a bag by which the frame members may be retained in a tightly closed position or released in a convenient manner to permit opening of the bag, the clasp being ornamental in appearance as well as efficient in operation.

A further feature is in the provision of a 10 concealed catch whereby the clasp is held in operative position, but which may by proper manipulation be disengaged permitting the 15 clasp to be raised from its normal holding position.

Another aim is to produce a device of this 20 character made entirely of sheet metal by ordinary stamping operations.

These objects are accomplished by the 25 novel construction and combination of parts hereinafter described and shown in the accompanying drawing, forming an essential part of this disclosure, and in which:—

Figure 1 is a perspective view of an embodiment of the invention, showing its application to a conventional type of frame bag.

Figure 2 is a longitudinal sectional view 30 of the device drawn to an enlarged scale and showing the manner by which it is anchored to a frame.

Figure 3 is a top plan view of the device 35 but showing the clasp as turned to an open position, affording an underside view thereof.

Figure 4 is a transverse sectional view taken on line 4—4 of Figure 2.

In the drawing a pair of bag frame members are designated by the numerals 10 and 10' respectively, the same being of ordinary 40 channel type, hinged at their angularly bent terminals to open and close as will be readily understood.

An anchor plate 11, shaped to extend over 45 the top surfaces of the channels 10 and 10', is provided with a narrow extension bent to enter an opening in the frame member 10 and then turned re-entrantly to be clenched as at 12; the plate is further secured on the same frame member 10 by a rivet 13 and its 50 opposite, wider end is curled to produce an eye 14 through which passes a hinge pin 15.

The pin 15 engages in registering openings 55 in a pair of lugs 16, the same being formed on one end of a clasp plate 17, provided at its lateral edges with right angled flanges

18 and 18' adapted to embrace the outer sides of the bag frame members 10 and 10', as best seen in Figure 4, these flanges being connected at their upper portions by a narrow front plate 19.

Enclosed between the flanges 18 and 18' is a flat U-shaped spring having arms 20 and 20', the spring being held at its bight 21 by a clip 22 formed from the clasp plate 17 and bent in such manner as to positively 65 retain the spring against the underside of the plate.

The arm 20' of the spring has at its outer, free end an inreaching lug 23 carrying a 70 projecting hook-shaped detent 24, the same being engageable in a keeper 25 rigidly mounted on the frame member 10' and held normally therein by action of the spring.

A rigid lateral projection 26 extends integrally from the outer edge of the spring 75 arm 20, through an opening in the flange 18, its end projecting past the flange to interlock against its outer side, retaining the spring arm firmly against the flange; at the opposite side is a similarly shaped projection 27, slidably mounted in an opening in the flange 18', the projection being formed on the outer edge of the spring arm 20', the arrangement being such that as the projection 27 is pressed inwardly of the clasp, the 80 spring arm 20' will be flexed and the detent 85 released from the keeper.

In operation, the sides are closed and the clasp is turned downward on the hinge axis 15, its side flanges cooperating to hold the 90 frame members in juxtaposition.

When the clasp plate is turned down, the bevelled lower edge of the detent 24 strikes the keeper and thus is caused to deflect until the hooked portion can enter the loop of 95 the keeper 25, into which it is forced by the flat spring, thus constituting a secure fastening.

To release the same, an operator's fingers are applied to the symmetrical projections 100 26 and 27, causing the latter to yield under pressure, retracting the keeper, permitting the clasp to be raised by the projections into the unlocked position shown in Figure 3.

Although I have described my improvements with considerable detail and with respect to a certain particular form of my invention, I do not desire to be limited to such details since many changes and modifications may well be made without de- 105

parting from the spirit and scope of the invention in its broadest aspect.

Having thus described my invention, what I claim as new and desire to secure by 5 Letters Patent, is:—

1. The combination with a pair of frame members movable towards and from each other, of a clasp hinged to one of said members to embrace both members, a keeper on 10 the other member, a pair of symmetric lateral extensions on said clasp, one of said extensions being rigid and the other yieldable, a spring in said clasp to normally project 15 said yieldable extension outwardly, and a detent on said spring engageable with said keeper.

2. The combination with a pair of bag frame members, of a hinged element fixed on one member, a keeper on the other member, a clasp operatively engaged by said 20 hinge element, said clasp having rigid sides to embrace both frame members when in one

position, a flat spring secured in said clasp, a detent carried by said spring to normally engage said keeper, and means accessible 25 from the exterior of said clasp to retract the spring and release the detent.

3. A bag fastener comprising in combination with a pair of hinged frame members, of a clasp hinged to one member, lateral 30 flanges on said clasp to straddle both members, a U shaped flat spring in said clasp between said flanges, means integral with said clasp to retain said spring, a detent on the free end of said spring, a keeper fixed on 35 the mating frame member in which said detent is normally engaged, and symmetrical projections on said spring, one of said projections being fixed relative to said flange and the other yieldingly carried on said 40 spring.

This specification signed and witnessed this 16th day of January, 1926.

WILLIAM C. HIERING.
